No. 821,313.

PATENTED MAY 22, 1906.

O. S. PULLIAM.
TRUCK END CASTING.
APPLICATION FILED OCT. 6, 1905.

UNITED STATES PATENT OFFICE.

OSWALD S. PULLIAM, OF PITTSBURG, PENNSYLVANIA.

TRUCK END CASTING.

No. 831,818.

Specification of Letters Patent.

Patented May 22, 1906.

Application filed October 8, 1905; Serial No. 231,649.

To all whom it may concern:

Be it known that I, OSWALD S. PULLIAM, a citizen of the United States, residing at Pittsburgh, in the county of Allegheny and State of Pennsylvania, have invented new and useful Improvements in Truck End Castings, of which the following is a specification.

The object of my invention is to provide a new and improved car-truck end casting.

10 A further object of the present invention is the production of a truck end casting of such a construction that column-bolts and their accompanying disadvantages are dispensed with.

15 To this end my invention consists of a new and improved truck end casting, in the novel features of construction, and in the combination of parts, all as hereinafter described and claimed.

20 In the accompanying drawings, which illustrate applications of my invention, Figure 1 is a side elevational view of a truck end casting constructed in accordance with my invention; Fig. 2, a detail end view; Fig. 3, a part plan and a part sectional view taken on line III III of Fig. 1, and Fig. 4, a detail showing a modification.

Referring to the drawings, the top arch-bar 1, the bottom or inverted bar 2, and the 30 tie-bar 3 are of the usual and well-known construction. As illustrated, these arch-bars and tie-bar are united by a pair of two-part columns 4, which extend over and securely clasp the arch-bars and tie-bar. Each 35 part of the two-part column is similar and interchangeable and is preferably formed with two upright members 5 and a cross member 6, joining the lower ends of the uprights 5. Cross members 6 are each formed 40 with a recess 7, the walls of which when the parts are applied to the lower arch-bar and tie-bar constitute a seat for said arch-bar and tie-bar. Each recess 7 extends throughout the length of the cross members 6 or from 45 one upright 5 to the other upright, and the seat formed provides a long continuous bearing for both the lower arch-bar and the tie-bar.

50 8 designates a projecting portion of cross members 6, and this portion, together with upper surface of each member 6, forms a seat for the springs 9.

Each of the uprights 5 is formed with a hooked portion 10, designed to clasp the top 55 arch-bar, and with an apertured lug 11.

The two parts constituting the column and

spring-supports are fastened together by bolts 12, passed through the lugs 11, and by a bolt 13, passed through apertured lugs 14, formed on the cross members 6. Attention 60 is called to the fact that lugs 11 project outwardly from the uprights and the connecting bolts 12 do not pass through the uprights.

In the modified form of my invention shown by Fig. 4 I employ in addition to the 65 parts above described a spring or sand plank 15. In this form the springs 9 are supported on said plank 15 instead of on the cross members and their projections. Spring-plank 15 is designed to rest on and be secured to the 70 cross members 6. When plank 15 is used, the cross members 6 need not be formed with the projecting portion 8, as in the form of Fig. 1.

What I claim is—

75 1. The combination with the arch-bars, of a truck end casting comprising a two-part column, each part formed to clasp the arch-bars and with projecting apertured lugs through which bolts are adapted to pass.

80 2. The combination with the arch-bar, of a truck end casting comprising a pair of columns and a spring-seat formed of two parts, each part having two upright members and a cross member joining the lower ends of the 85 uprights, each cross member formed with a recess extending throughout the length of the cross member and adapted when the parts are assembled to form a seat for the lower arch-bar.

90 3. The combination with the arch-bars, of a truck end casting comprising a pair of columns, each column formed of two similar parts, each part formed to clasp the arch-bars, and means for connecting the two parts 95 constituting a column comprising apertured lugs formed integral with each column part, and bolts adapted to pass through said lugs.

4. A truck end casting comprising a pair of columns and a spring-seat formed of two 100 similar and interchangeable parts, and means for connecting the parts comprising projecting apertured lugs formed integral with each part.

105 5. A truck end casting comprising a pair of columns and a spring-seat formed of two similar and interchangeable parts, each part having two upright members and a cross member joining the lower ends of the uprights, each of the said members formed with apertured lugs through which bolts are adapted to pass.

110 6. The combination with the arch-bar, of

a truck end casting comprising a pair of columns and a spring-seat consisting of two similar parts, each part having two upright members and a cross member joining the lower ends of the uprights, each cross member formed with a recess extending from one upright to the other, projecting apertured lugs on the uprights, and a centrally-disposed apertured lug on each cross member.

10 7. A truck end casting comprising a pair of columns and a spring-seat formed of two similar parts, each part having two upright members and a cross member joining the lower ends of the uprights, means for con-

necting the uprights of one part to the corresponding uprights of the other part comprising projecting apertured lugs and bolts passing through said lugs, and means for connecting the cross members of each part comprising a centrally-located apertured lug 20 formed on each cross member.

In testimony whereof I affix my signature in presence of two subscribing witnesses.

OSWALD S. PULLIAM.

Witnesses:

MARGARET HUGHES,
W. G. DOOLITTLE.
